DESIGN FOR A CAPSULE TRAY

Matthew J. Fagan, Chicago, Ill., assignor to W. C.
Ritchie & Company, Chicago, Ill., a corporation of Illinois

Application July 31, 1940, Serial No. 94,074

Term of patent 14 years

To all whom it may concern:

Be it known that I, Matthew J. Fagan, a citizen of the United States, residing in Chicago, in the county of Cook and State of Illinois, have invented a new, original and ornamental Design for a Capsule Tray, of which the following is a specification, reference being had to the accompanying drawing, forming a part thereof.

In the drawing:

I claim:

The ornamental design for a capsule tray, as shown.

MATTHEW J. FAGAN.
